REINFORCED CYLINDER

Phillip P. Newcomb, Manchester, Conn., assignor
to United Aircraft Corporation, East Hartford,
Conn., a corporation of Delaware

Application September 27, 1940, Serial No. 358,682

7 Claims. (Cl. 123—171)

This invention relates to improvements in engine cylinders and has particular reference to an improved cylinder construction for an air cooled internal combustion engine such as is conventionally employed for the propulsion of aircraft.

An object of the invention resides in the provision of an improved engine cylinder of the character indicated in which adequate strength with minimum weight is provided by utilizing a strong durable metal, such as steel, for the load carrying parts of the cylinder and utilizing a relatively light weight metal such as an aluminum alloy to provide the heat radiating surfaces and enclosures for valve operating mechanisms.

A further object resides in the provision of an improved engine cylinder of the character indicated in which the valve operating mechanism is directly supported on the load carrying part of the cylinder and the light weight metal parts are substantially free of loads incident to valve operation.

A still further object resides in the provision of an improved engine cylinder of the character indicated having an integral cylinder and head liner of a strong durable metal, such as steel, to which are connected valve port liners and valve mechanism supports of the same or a similar material, and a cooling and valve mechanism enclosing structure of a light weight metal, such as an aluminum alloy, cast onto the strong metal structure and in which said valve port liners assist in maintaining the cooling and valve mechanism enclosing structure on the strong metal liner and also assist in supporting the loads incident to valve operation.

Other objects and advantages will be more particularly pointed out hereinafter or will become apparent as the description proceeds.

In the accompanying drawings, in which like reference numerals are used to designate similar parts throughout, there is illustrated a suitable mechanical embodiment for the purpose of disclosing the invention. The drawings, however, are for the purpose of illustration only and are not to be taken as limiting or restricting the invention since it will be apparent to those skilled in the art that various changes in the illustrated construction may be resorted to without in any way exceeding the scope of the invention.

In the drawings, Fig. 1 is a vertical sectional view through an improved engine cylinder constructed according to the invention.

Fig. 2 is a sectional view of the intake port portion of the cylinder shown in Fig. 1 taken on

the line 2—2 of Fig. 1 and on a plane disposed at right angles to the plane of the section of Fig. 1, and

Fig. 3 is a sectional view similar to Fig. 2 of the exhaust port portion of the cylinder shown in Fig. 1 taken on the line 3—3 of Fig. 1.

Referring to the drawings in detail, the numeral 10 generally indicates a cylinder liner. This liner 10 may have an annular external retaining flange 12 by means of which it is bolted or otherwise secured to an engine crankcase in a desired or usual manner. Below the flange 12 there may be a skirt portion 14 adapted to extend within the engine crankcase and above the flange there may be a cylindrical barrel portion 16 terminating in a partly spherical or dome shaped head portion 18 through which are provided an intake opening, as indicated at 20, and an outlet opening, as indicated at 22, and one or more spark plug apertures, as indicated at 24.

An intake valve port liner 26 and an exhaust valve port liner 28 are secured to the head portion 18 within the respective intake and exhaust openings 20 and 22 by some suitable means, such as welding or brazing. While, in some cases, it might be entirely feasible and desirable to form the valve port liners integrally with the main cylinder liner 10, it will usually be found more economical and practical to construct these port liners as separate members by forming them as castings or sheet metal stampings and then securing them in place upon the main cylinder liner in the manner indicated above. Adjacent to each of the liners 26 and 28 there is provided a valve mechanism support, as indicated at 30 for the intake valve mechanism and at 32 for the exhaust valve mechanism. Each of these valve mechanism supports may be of the form of a generally rod like member having a forked or bifurcated end portion for supporting the rocker arm of the respective valve mechanism, and means at the end opposite the fork for securely connecting the support to the head portion 18 of the main cylinder liner. Thus, the intake valve mechanism support may be provided with a forked or bifurcated end portion comprising the legs 34 and 36 apertured to receive the rocker arm bearing bolt 38 and may have its end opposite the fork end welded or brazed into a tubular member 40 which is in turn welded or brazed to an aperture in the head 18. The tubular member 40 has its outer end cut on a bias or diagonal, as indicated at 42, to avoid a concentration of bending stresses through any one transverse plane of the supporting column 30. The

40
45
50

exhaust valve mechanism support 32 is similarly forked to provide the legs or prongs 44 and 46 which are apertured to receive a bearing bolt, similar to the bolt 38 for the exhaust valve rocker arm. At its end opposite the fork the supporting column 32 is also received in a tubular member 48 which is welded into an aperture provided in the head portion 18 and provided with a biased or diagonal outer end 50 to distribute bending stresses between the supporting column and the liner 10 along a predetermined length of the column to avoid undue concentration of stresses.

The intake port liner 26 is particularly illustrated in Fig. 2 and comprises, in general, a conduit providing a substantially streamlined passage from the manifold or intake pipe connection 52 to the inlet aperture 20, an intake valve stem guide 54 and a valve seat 56 provided in the thickened portion of the liner in the aperture 20.

The exhaust port liner 28 is particularly illustrated in Fig. 3 and comprises a conduit of heat resisting material leading from the exhaust aperture 22 to the exterior of the cylinder head provided with a valve stem aperture 58 and a valve seat insert 60 preferably formed of some hard resistant material which is not readily subject to erosion by the hot exhaust gases.

The heat radiating and valve mechanism enclosing structure, referred to above, comprises a matrix or coating of a suitable metal such as an aluminum alloy cast onto the exterior of the liner 10 from a point somewhat above the flange 12 and entirely over the head portion 18. This cast layer is provided with extensions one of which, as indicated at 64, surrounds the intake port liner 26 and another, as indicated at 66, surrounds the exhaust port liner 28. At the end of the extension 64 there is provided an intake valve rocker box 68 cast integrally with the extension 64 and at the end of the extension 66 there is provided an integral exhaust valve rocker box 70. The intake rocker box 68 extends from the valve guides 54 past the bifurcated end of the rocker arm support 30 and includes a connection 72 for the outer end of the valve push rod cover. A web or wall 74, extending from the rocker box to the matrix over the head 18, surrounds and encloses the stem portion of the support column 30. The exhaust valve rocker box 70 likewise extends from the valve guide 76 past the bifurcated end of the exhaust valve rocker arm support 32 to a connection 78 for the outer end of the exhaust valve push rod cover. A web or wall 80, integral with the liner encasing matrix and the rocker box 70, extends from the rocker box to the matrix and surrounds the exhaust valve rocker arm support 32. The matrix 62 is provided with suitable cooling fins 82 which may be formed in any suitable or desired manner as by casting the matrix over the inner edges of sheet metal fins as illustrated, or by casting or otherwise providing integral fins on the matrix.

There is thus provided an improved cylinder construction having an inner strength member of a strong and durable metal and having the valve operating mechanism secured to the strength member in such a manner that the valve operating loads are applied directly to the strength member. There is also provided a construction in which the light metal casing is reinforced by the valve port liners and in which the liners assist in retaining the casing in operative position upon the strength member and in heat transfer-

ring contact therewith and also in which, because of the interconnection of light metal between the valve port liners and the valve mechanisms supports, the supports are reinforced by the valve port liners particularly against bending stresses and other loads which are not directly in line with the axes of these supports.

While a suitable mechanical embodiment has been hereinabove described and illustrated in the accompanying drawings for the purpose of disclosing the invention, it is to be understood that the invention is not limited to the particular embodiment so described and illustrated but that such changes in the size, shape and arrangement of the various parts may be resorted to as come within the scope of the subjoined claims.

Having now described the invention so that others skilled in the art may clearly understand the same, what it is desired to secure by Letters Patent is as follows:

1. An engine cylinder comprising, a barrel and head liner of a metallic material of high structural strength, intake and exhaust port liners of a metallic material of high structural strength secured to said barrel and head liner, a casing of light weight metal covering said port liners and a portion of said barrel and head liner, and supports for valve actuating mechanism of a metallic material of high structural strength attached to said barrel and head liner and imbedded in said casing near said port liners.

2. An engine cylinder comprising, a steel cylinder barrel having an integral head portion provided with an intake and an exhaust opening, a steel intake port liner secured to said barrel in said intake opening, a steel exhaust port liner secured to said barrel in said exhaust opening, an aluminum casing surrounding said port liners and a portion of said barrel, valve actuating mechanism enclosures formed integrally with said casing, and steel supports for said valve actuating mechanisms secured to said barrel near the respective port liners and projecting through said casing and into the respective valve actuating mechanism enclosures to support the valve actuating mechanisms disposed therein.

3. The arrangement as set forth in claim 2 in which each of said supports comprises a rod like portion secured at one end to said barrel and a forked portion integral with said rod like portion and apertured to receive the ends of a valve actuating mechanism bearing pin.

4. An engine cylinder comprising an integral forged barrel and head liner, an intake port liner and an exhaust port liner secured to said head liner, a cast fin retaining casing and integral valve mechanism enclosures, and forged supports for valve actuating mechanisms extending from said head liner through said casing into said enclosures for supporting valve actuating mechanisms from said head liner.

5. In combination with an engine cylinder head liner of a metallic material of high structural strength and a casing of light weight metal having a structural strength less than that of said high strength material covering said head, a valve actuating mechanism support comprising a tension member of high structural strength secured at one end to said head liner and imbedded in said casing and provided at its opposite end with structure for supporting valve actuating mechanism on said cylinder head.

6. In combination with an engine cylinder head liner of a metallic material of high structural strength, a casing of light weight metal having

a structural strength less than that of said high strength material covering said head, a valve actuating mechanism support comprising a tension member of high structural strength secured at one end to said head liner and provided at its opposite end with structure for supporting said valve actuating mechanism and imbedded in said casing both adjacent its juncture with the head liner and at its valve actuating mechanism supporting end.

7. An engine cylinder comprising a barrel and head liner of a metallic material of high struc-

tural strength, a valve port liner of metallic material of high structural strength secured to said barrel and head liner, a casing of light weight metal of lower structural strength than said first mentioned metallic material covering said port liner and a portion of said barrel and head liner, and a valve actuating mechanism support of metallic material of high structural strength attached to said barrel and head liner and imbedded 10 in said casing near said liner.
